CARTON OR SIMILAR ARTICLE

Marion R. Mulford, Lebanon, Ohio, assignor to
 Hewett P. Mulford & Company, Lebanon, Ohio,
 a partnership consisting of Hewett P. Mulford
 and Marion R. Mulford

Application July 13, 1939, Serial No. 284,297

5 Claims. (Cl. 47—37)

This invention relates to cartons and more particularly to a carton which is particularly adaptable for use as a plant package and growing container and which in this connection provides a number of advantages. The particular carton illustrated embodies a number of the features described and claimed in copending applications in the names of Mulford and Gray, Serial No. 124,195, filed February 5, 1937, which issued into Patent No. 2,238,818, April 15, 1941, and Serial No. 124,196, filed February 5, 1937, which issued into Patent No. 2,150,453, March 14, 1939.

It is an object of my invention to provide certain improvements upon the packages described in the above mentioned applications, and in general my objects include the provision of a neat and attractive package which is of relatively simple manufacture, which will efficiently serve its purpose, and which will have considerable "eye appeal."

These and other objects of my invention which will be set forth hereinafter or will be apparent to one skilled in the art upon reading these specifications, I accomplish by that certain construction and arrangement of parts of which I shall describe certain exemplary embodiments.

Reference is now made to the drawing which forms a part herein, and in which:

Figure 1 is a plan view of a blank from which a portion of the carton is made;

Fig. 2 is a plan view of the blank from which a second portion of the carton is made;

Fig. 3 is a plan view of a third blank used in connection with my carton;

Fig. 4 is an exploded perspective view of the assembly with parts broken away to show the inner construction;

Fig. 5 is a cross sectional view taken on the line 5—5 of Fig. 4 but with the carton in its assembled condition;

Fig. 6 is a partial detail cross sectional view taken on the line 6—6 of Fig. 4, and

Fig. 7 is a plan view of a display element which may be used in connection with the package.

Briefly, in the practice of my invention, I provide a moisture-proof container of any well known type, said container being preferably rectangular in cross section and having sloping sides as indicated at 10. This container will in the usual manner be filled with a plant growth supporting material 11 and will contain one or more bulbs 12, or growing plants. In order to make a package containing such a bulb or plant pleasing to the eye and not unpleasant to the touch as is the case with most impregnated materials, it is

desirable to provide some attractive covering arrangement and it is preferable that this arrangement should embody a watering well whereby the plant may be watered without wetting the surface on which the package rests, and means whereby a number of cartons may be stacked upon each other without damage to the growing bulb. Preferably the arrangement should also include a cover element to retain the plant growth supporting material and prevent its dislodgment from the container. Referring to Fig. 2, I have shown a blank having a portion indicated generally at 13 forming the top and having side flaps 14 and 15 and a bottom flap 16, articulated to the side flap 15. Preferably the flap 16 will be provided with an articulated interlocking tongue 17 adapted to interengage with the slots 18 in the flap 14, as illustrated in Fig. 4.

The portion 13 is preferably provided with flaps 20 which serve to continue the finished appearance of the top as in the case of the down-turned flaps 14 and 15, and thus prevent any raw edges from showing at the top of the package. In the flaps 14 and 15 I provide U-shaped cuts generally shown at 21, which cooperate with another portion of the package as will be described hereinafter. I prefer to cut out the center of the portion 13, as indicated at 22, and to provide score lines 23 whereby flaps 24 are formed, which are then folded downwardly along the score lines 23 and form attaching elements for the member 25, shown in detail in Fig. 3.

The member 25 is preferably, although not necessarily, square in cross section and has a central perforation 26 to permit plant growth, and is provided with slots 27 to cooperate with the tabs 24, as shown most clearly in Figs. 4, 5 and 6. Articulated to the four sides of the member 25 are the flaps 28 which are turned up as is clearly shown in Figs. 4 and 6.

It will be noted that when the members illustrated in Figs. 2 and 3 are assembled the member 25 forms a top element or cover element for the inner moisture-proof container disposed below the upper edges thereof, and that the flaps 24 form vertical walls defining with the member 25 a watering well. The flaps 28 turn upwardly behind the flaps 24 to cooperate in preventing access of water outside the inner moisture-proof container. In assembling, it will be noted as shown in Fig. 5 that the walls of the inner container 10 extend upwardly above the member 25 and outside of the flaps 28, whereby it is insured that any water poured into said watering well

has access only into the interior of said moisture proof container.

In order to give a finished appearance to the whole package I provide an outer encircling member shown in Fig. 1, comprising four walls 30, 31, 32, and 33. The wall 33 may be provided with a flap 34 having an interlocking member 35 adapted to engage with a slot 36 in the portion 30, or it may be adhesively fastened or fastened by stitching or the like. Flaps 37 are articulated to the tops of each of the walls 30 to 33 inclusive, so that when the entire article is assembled no raw edges will be visible and the package will have a finished appearance and will be reinforced and strengthened.

Referring to Fig. 5 it will also be noted that the flaps 21 which are slightly bent outwardly from the walls 14 and 15 will, when the outer cover is slid upwardly and then returned downwardly, engage under the down-turned flaps 37 of the outer encircling member, thus providing a further interlock, and pulling the encircling member closer around the inner container.

In Fig. 7 I have shown a member 40, the upper portion of which may be died out and pointed in simulation of a trellis or the like. The lower portion 41 constitutes a flap which may be inserted between an inner and outer side wall, affording a pleasing background for the growing bulb or plant.

It will be clear that I have thus provided a carton consisting fundamentally of an inner moisture-proof plant container and an outer finishing member consisting in the particular case illustrated of three pieces, one of which (element 25) provides a retaining cover for the plant growth supporting material and cooperates in the formation of a watering well, the second of which (element 13) completes the formation of the watering well and provides stacking ledges and which interlocks about said plant containing element, and a third element of which provides a pleasing finished appearance for the package exhibiting no raw edges, and which, by virtue of the fact that it need not come in contact with water, may be made of any suitable non-waterproof material and finished or decorated in any desired manner.

It will be understood that modifications may be made in my invention without departing from the spirit thereof, and that I do not intend to limit myself otherwise than as pointed out in the claims which follow.

Having now fully described my invention, what I claim as new and desire to secure by Letters Patent, is:

1. In a carton, an inner member having a

tapered form and an outer covering member of annular form and having a taper corresponding with said inner member, the upper edge of said outer member being inwardly down-turned and 5 said inner member being provided with upwardly directed outwardly extending tongues disposed for lapping engagement with said inwardly down-turned edge for retaining said members together.

10 2. In combination with an inner carton element of tapered form, an outer encircling band having a taper corresponding with said inner carton element and having an inwardly down-turned upper edge and means on said inner carton element to engage under said down-turned edge for locking said inner carton elements and band together.

15 3. In a carton, an inner portion comprising a top and a bottom, and at least two sides connecting said top with said bottom, said bottom being similar and smaller in cross section relative to said top, and an upwardly directed outwardly extending tongue in a side wall, and an outer annular covering element corresponding in shape 20 to said inner portion and having an inwardly down-turned upper edge adapted to engage with said tongue to hold the parts in operative relation.

4. In a carton, an inner moisture-proof container having tapered walls, a member providing an apertured cover for said inner container disposed below the top thereof and provided with means for holding said member in operative relationship with said inner container, and an 25 outer encircling band shaped to closely fit said tapered walls, and having an inwardly down-turned upper edge and means on said member cooperating with said edge for holding said band in operative relationship with said container and member.

5. In a carton, an inner moisture-proof container having tapered walls, a member providing an apertured cover for said inner container disposed below the top thereof and provided with 30 means for holding said member in operative relationship with said inner container, and an outer encircling band shaped to closely fit said tapered walls, and having an inwardly down-turned upper edge and means on said member cooperating with said edge for holding said band in operative relationship with said container and member, said means including outwardly extending upwardly directed tongues on said member 35 adapted to engage under said inwardly down-turned upper edge of said encircling band.

MARION R. MULFORD.
